UNITED STATES PATENT OFFICE.

CHARLES B. FOSTER AND WILMOT W. GLIDDEN, OF OAK PARK, ILLINOIS.

VACUUM DUST-REMOVER.

977,380.

Specification of Letters Patent. Patented Nov. 29, 1910.

Application filed February 21, 1908. Serial No. 416,975.

To all whom it may concern:

Be it known that we, CHARLES B. FOSTER and WILMOT W. GLIDDEN, citizens of the United States, residing at Oak Park, in the county of Cook and State of Illinois, have invented certain new and useful Improvements in Vacuum Dust-Removers, of which the following is a full, clear, and exact description.

10 Our invention relates to certain new and useful improvements in vacuum dust removers and more particularly to improvements in the hand implement of devices of this kind.

15 This invention is designed to furnish a simple and practically inexpensive device for removing dust and other small particles from carpets, rugs and the like.

20 One of the objects of this invention is to furnish means whereby the nozzle may be held firmly upon the carpet or rug by the operator, regardless of the angular position of the handle with respect to the nozzle, and thereby maintain the dust inlet in the proper 25 relation with the object to be cleaned.

Another object is to simplify the construction of devices of this type, and to avoid the necessity of providing packings and the like to prevent leakage between the movable 30 members of the nozzle.

Other objects and advantages will appear in the course of this specification and the essential features will be more particularly pointed out in the claims.

35 The invention is clearly illustrated in drawings furnished herewith in which—
Figure 1 is a perspective view of a cleaner embodying our invention. Fig. 2 is an under plan view. Fig. 3 is a side view with the handle portion broken away. Fig. 4 is a cross section taken through the nozzle. Fig. 5 is a perspective view of a fragment of a hood. Fig. 6 is a vertical section taken on the line 6—6 Fig. 3. Fig. 7 is a plan view 40 of a fragment of the foot. Fig. 8 is a cross section on the line 8—8 Fig. 2. Fig. 9 is a plan view of a slightly modified form of the device, with a portion of the handle broken away. Fig. 10 is a side view thereof. Fig. 45 50 55 11 is a central vertical section of said modified form, and Fig. 12 is a side view of one of the members of the nozzle portion.

Referring first to Figs. 1 to 8 inclusive of the drawings, A, represents a handle that is arranged to be connected to a hose 10, which leads to a suitable vacuum apparatus for

producing the necessary suction. The handle, A, is in the form of a tube and has secured upon its lower end a nozzle B, which is moved back and forth along the carpet or rug in the usual manner in cleaning the same. The nozzle is preferably constructed of two members 20—21, the member 20, being tubular in form and fitting within the open lower face of the member 21. The member 20, acts as a pressure foot and contains a dust inlet upon its lower face, which dust inlet is in the form of a series of perforations 22, extending longitudinally of the pressure foot, and through which the dust enters the nozzle and this lower side is flattened to present a flat pressure face for contact with the object to be cleaned. The upper side of the wall of the foot 20, is slotted longitudinally as shown at 23, thus forming a direct passage way through the foot 20, and extending through the entire length thereof. Shoes 24, are provided upon the ends of the foot 20, which shoes practically form continuations of the flat lower face, the object being to give to the nozzle a large base or bearing surface upon the carpet, so that pressure upon the nozzle from above will always tend to hold the perforated pressure face in close contact with the carpet.

The hood 21, incloses the slot in the upper side of the foot 20, and contains two bearing faces 25 that fit snugly upon the exterior walls of the foot 20. The hood and foot portions are pivotally connected together, as by lugs 26, which project out from the end walls 27, of the foot portion, and ears 28, that are secured to the hood. As shown, the ears 28 are in the form of plates, that are screwed to the end walls 29, of the hood. The pivot connection is provided merely to loosely connect the two parts together. As soon as suction is applied, the foot portion is drawn into firm contact with the bearing faces 25, of the hood, and the pivot connections temporarily lose their usefulness. A nipple 30 extends out from the hood 21 and is screwed upon the handle A, forming the connection between the handle and nozzle.

In the modified form, illustrated in Figs. 9 to 12 inclusive, A' represents the tubular handle and B' the nozzle, the pressure foot of which is rotatably mounted with respect to said handle. The nozzle contains two members 20', 21', the member 21', being secured upon the handle A', by means of a

nipple 21^a, and rotatably connected to the member 20' by means of a hood 21^b that partially encircles the member 20'. Said member 20' acts as the pressure foot and 5 contains inlet perforations 22' through which the dust enters, and an outlet opening 23' is provided which registers with the opening in the nipple 21^a, thereby affording a direct passageway through the nozzle to the handle. The member 21', contains a 10 segmental bearing face upon its lower side upon which the pressure foot is seated, and said member 21', is held against longitudinal movement upon the pressure foot by suitable means here shown as pins or screws 21^c, that pass through slots 21^d formed in the hood 21^b. The hood 21^b, has a segmental bearing face, somewhat more than a semi-cylinder in extent, and the nozzle member 20^a, is cylindrical and fits in the concave 15 face of the hood 21^b. The cylindrical wall of the nozzle member 20^a, is flattened on its lower side to form the face which bears upon the object to be cleaned, and also to facilitate 20 the removal or replacement of the member 20^a, on the hood without the removal of the shoes 24^a. This is accomplished by unscrewing the screws 20^b, and turning the member 20^a, until its flat side comes in front 25 of either edge of the hood, whereupon the member 20^a, may be removed laterally through the gap in the hood. Bearing shoes 24^a, are secured upon the pressure foot, 20' to provide means for preventing the tilting 30 of the pressure foot, which would otherwise be occasioned on account of the shifting of the handle in the use of the device upon the object to be cleaned.

In operating the cleaner, suction is applied to the hose 10, and the cleaner is moved 40 back and forth across the carpet, rug or other like object to be cleaned, the flat bearing face of the foot being held in close contact with the carpet. In moving the nozzle, 45 back and forth, the hood is caused to rock or turn upon the foot portion, by reason of the fact that the angular position of the handle is constantly changing with respect to the pressure foot and often the handle is 50 swung down quite close to the floor, as for instance when the nozzle is pushed under some article of furniture. In order that the best results may be had, the flat bearing face should be held in firm contact with the object that is being cleaned, inasmuch as the suction then causes air to pass through the 55 nap of the carpet from both sides of the perforations before passing into the foot. In this manner a more thorough cleaning of the 60 object can be had because all of the suction force is utilized and practically none is lost. Furthermore, the nozzle is under control of the operator and the pressure upon the carpet can be maintained at his will. We 65 are thus enabled not only to remove the sur-

face dust but practically all of the dust that has lodged in the body of the carpet. This is practically impossible where the nozzle travels lightly over the surface of the carpet or part of the slot is uncovered so that the air will rush directly into the nozzle without first passing through the nap or body of the article to be cleaned. It will be perfectly obvious that the pressure which the operator exerts in operating the cleaner will at all 70 times maintain the foot in an upright position upon the carpet, and that no particular care need be taken by the operator to do this as the flat bearing face will practically prevent the tilting or rocking of the foot. 75

We realize that various alterations and modifications of the device are possible without departing from the spirit of our invention, and we do not therefore desire to limit ourselves to the exact construction shown 80 and described except as particularly pointed out in the claims appended hereto.

We claim as new and desire to secure by Letters Patent:

1. A vacuum dust remover, comprising a 90 hollow handle arranged to be connected with a suction apparatus, and a nozzle secured upon said handle and opening into the same, said nozzle having two relatively movable members, one member being rigidly 95 secured upon the handle and having a segmental bearing face, and the other member being cylindrical and rotatively mounted on said segmental bearing face and having a flattened portion in its cylindrical wall containing a dust inlet, and transverse bearing shoes upon the ends of said second named nozzle member for maintaining the same in an upright position upon the object to be 100 cleaned. 105

2. A vacuum dust remover, comprising a hollow handle arranged to be connected with a suction apparatus, a hollow nozzle member rigidly secured upon one end of said handle and opening into the same, and having a transversely extending hood which is formed with a segmental bearing face of greater extent than a semi-cylinder, a tubular nozzle member fitted to the cylindrical bearing face of the first named nozzle member and rotatively mounted therein, said second named nozzle member being formed with a flattened bearing face in its cylindrical wall containing a dust inlet, and having relatively long bearing shoes for maintaining the same in an upright position upon the object to be cleaned. 110 115

3. A vacuum dust remover, comprising a hollow handle arranged to be connected to a suction apparatus, a tubular hood connected to and opening into said handle, said hood being formed with a segmental bearing face having an opening therein, a tubular nozzle member fitting said segmental bearing face, and having an opening registering with the 120 125 130

opening in the bearing face of the hood, said nozzle member being formed with a flattened portion in its cylindrical wall containing a dust inlet and having bearing shoes for maintaining the same in an upright position upon the object to be cleaned.

4. A vacuum dust remover, comprising a hollow handle arranged to be connected to a suction apparatus, a hood secured to one end of the handle and having a segmental bearing face of greater extent than a semi-cylinder; a tubular nozzle member rotatively mounted in said bearing face and having an opening communicated with the interior of the handle, said nozzle member being formed with a flattened portion in its cylindrical wall containing a dust inlet, bearing shoes upon said nozzle member and means for preventing endwise movement of the nozzle member upon the hood.

5. A vacuum dust remover, comprising a

hollow handle, a transversely extending nozzle swiveled thereon, means for preventing endwise movement of the nozzle upon the handle and bearing shoes upon the ends of 25 the nozzle, said nozzle having a flattened bearing face containing a series of dust inlet perforations arranged longitudinally thereof.

In witness whereof, this application has been executed by CHARLES B. FOSTER at 30 Buffalo, N. Y., this 10th day of February, 1908, and by WILMOT W. GLIDDEN at Oak Park, Ill., this 12th day of February, 1908.
